UNITED STATES PATENT OFFICE.

MATTHEW J. REILLY, OF NEW YORK, N. Y., ASSIGNOR OF ONE-HALF TO THOMAS F. EARLY, OF WEST NEW BRIGHTON, NEW YORK.

SAFETY ATTACHMENT FOR GAS-ENGINE CRANKS.

1,276,694.

Specification of Letters Patent. Patented Aug. 20, 1918.

Application filed March 19, 1918. Serial No. 223,339.

To all whom it may concern:

Be it known that I, MATTHEW J. REILLY, a citizen of the United States, and a resident of the city of New York, West New Brighton, borough of Richmond, in the county of Richmond and State of New York, have invented a new and Improved Safety Attachment for Gas-Engine Cranks, of which the following is a full, clear, and exact description.

This invention relates to cranking devices for automobiles or other internal combustion engines and has particular reference to means to prevent injury to the operator at the time of the cranking operation, due to premature ignition or back-firing of the engine.

Another object of the invention is to provide an attachment adapted to be readily applied to existing engines without material alteration of the structure of such engines.

With the forgoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view of the principal parts of my improvement, a part of the bracket being in horizontal section.

Fig. 2 is a vertical transverse section on the line 2—2 of Fig. 1; and

Fig. 3 is a vertical longitudinal section on the line 3—3 of Fig. 1.

Referring now more particularly to the drawings I show at 10 a fragment of the front end of an automobile, 11 being the usual crank having a shaft 12 adapted for coöperation with the shaft extension 13 through a clutch 14, when the crank is shoved rearward against the force of a spring 15 and rotated toward the right or in a clockwise direction.

The above features being conventional I will now describe my attachment or improvement which comprises a rigid yoke or bracket 16 adapted to be fixed in any suitable manner to the front part of the engine

and at the right side of the crank shafts 12 and 13.

17 indicates a short spindle journaled in the left side of the bracket 16 parallel to the crank shaft and carrying the compound gear member comprising a ratchet wheel 18 and a long toothed pinion 19. The pinion 19 has constant meshing engagement with a toothed gear 20 fixed to the crank shaft 12, the teeth of the pinion 19 are made much longer than those of the gear so as to accommodate the gear to its forward and rearward shifting movements incident to the shifting of the crank shaft 12 into and out of mesh with the auxiliary shaft 13.

The ratchet wheel 18 and connected pinion 19 are adapted to rotate freely toward the left as a result of the rotation of the gear 20 toward the right so that there is no interference to the intended or proper rotation of the crank, occasioned by the ratchet wheel.

21 and 22 indicate a pair of pawls, one longer than the other, and both adapted to coöperate in succession with the teeth of the ratchet wheel. In saying that one pawl is longer than the other I wish to be understood as meaning that the effective length is greater than that of the other so that the ends or points of the pawls are relatively offset so that but one will be operative at any one time. The offset between the ends of the teeth approximately is equal to one half of the circumferential length of each ratchet tooth. By this construction, therefore, I am able to make a ratchet wheel of maximum strength and yet insure that the extent of reverse movement permitted thereby will be very slight in practice. In carrying out this feature of my invention I pivot the two pawls approximately coaxial of each other on a pair of crossheads 23 and 24, the pivots being indicated at 25. Obviously, however, the pivots might be offset relatively so that the pawls might be of the same length and yet have the same offset advantage for their points as above set forth.

These crossheads as shown best in Fig. 3 are preferably of the same character each being slidable along a pair of guide rails 26 and a central guide rail 27. The guide rails 26 constitute beads or flanges formed along the front and rear bars of the bracket 16 while the bar 27 extends substantially mid-

way between those two bars or rails. Each crosshead is held normally abutting squarely against the vertical portions of the bracket by virtue of a strong buffer or cushioning spring 28 surrounding a stem 29 adapted to slide through the right hand end 30 of the bracket.

Each pawl is held down in engagement with the ratchet wheel by means of a light 10 leaf spring 31.

The operation of my improvement may be briefly summarized as follows: To crank the engine the operator grasps the crank 11 and after shoving it rearward as usual to 15 connect the two crank shaft elements 12 and 13 will turn the crank in the usual manner. During this rotation of the crank shaft and gear 20 connected thereto the pinion 19 and ratchet wheel 18 will be given 20 a corresponding rotation in the opposite direction, the teeth of the ratchet wheel turning freely under the pawls. In the event of back-fire of the engine which so frequently is the cause of the breaking of the 25 wrist or arm of the operator, when the crank handle is thrown around striking the operator, the pawls are in position to insure that at least one of them will be engaged by the undercut face of a ratchet tooth, so 30 stopping the undesired reverse rotation of the crank shaft by means of the constant intermeshing engagement of the pinion 19 and the gear 20. The mounting of the 35 pawls on the resiliently mounted crossheads is primarily for the purpose of cushioning the rearward impact, but the springs 28 are calculated to be strong enough to prevent sufficient reciprocation of the pawls to the extent of permitting the pawls to fail in 40 their purpose.

I claim:

1. The combination with an engine crank adapted to rotate in one direction, of a safety attachment to prevent the rotation 45 of the crank in the opposite direction, said attachment comprising a toothed gear fixed to the crank shaft, a pinion meshing constantly with the gear, and pawl and ratchet devices coöperating with the pinion to prevent the same from undesired reverse rotation.

2. In a safety attachment for engine

cranks, the combination with a crank and a gear fixed thereto for rotation in the same direction, of a pinion having constant 55 meshing engagement with the gear, a ratchet wheel fixed to the pinion and adapted to rotate therewith around the same axis, and a pair of pawls of different lengths coöperating in succession with the 60 teeth of the ratchet wheel.

3. The combination with relatively fixed and slidable coaxial shaft members having clutch teeth, means to normally hold the clutch teeth separated and the crank attached to one of said members whereby the clutch teeth may be engaged, of a safety attachment comprising a gear fixed to the 65 slidable shaft member, a long pinion having constant meshing engagement with the gear, a fixed bracket in which the pinion is journaled for rotation around a fixed axis, a ratchet wheel fixed to the pinion and adapted to rotate around the same axis, a crosshead mounted in the bracket for 70 slideable movement toward and from the ratchet wheel, a strong spring acting upon the crosshead to hold it normally adjacent to the ratchet wheel, and a pawl pivoted upon the crosshead and coöperating with the 75 teeth of the ratchet wheel, substantially as set forth.

4. The herein described safety attachment to prevent the reverse rotation of an engine crank shaft, said attachment comprising a rigid bracket, a ratchet wheel journaled in the bracket on an axis parallel to the crank shaft, front and rear bars having guide rails perpendicular to the axis of the ratchet wheel, a central guide rail fixed 85 midway between the aforesaid rails, a pair of crossheads slidably mounted upon the respective side rails and central rail, strong cushioning means between the crossheads and the remote portion of the bracket tending to resist such sliding movement, longer and shorter pawls pivoted upon the crossheads and coöperating in succession with the teeth of the ratchet wheel, and positive gear connections between the crank shaft 90 and the ratchet wheel, substantially as set forth.

MATTHEW J. REILLY.
